UNITED STATES PATENT OFFICE.

JOHN W. HASBURG, OF CHICAGO, ILLINOIS.

APPORTIONING-MACHINE.

1,147,393.

Specification of Letters Patent. Patented July 20, 1915.

Application filed January 8, 1912. Serial No. 669,911.

To all whom it may concern:

Be it known that I, JOHN W. HASBURG, a citizen of the United States, residing at Chicago, in the county of Cook and State of Illinois, have invented certain new and useful Improvements in Apportioning-Machines, of which the following is a specification.

My invention relates to improvements in apportioning machines, and has especial reference to devices of this class adapted for proportioning small quantities of material.

One of the objects of my invention is to provide a machine adapted to divide valuable mastic material, such as gold paint and the like, and deposit it in small, admeasured and equal quantities on successively presented receiving surfaces, such as glass palettes or the like.

Such machines, therefore, must be capable of handling the peculiarly sticky material, and on account of the intrinsic value of such material it must operate with the greatest precision that the distribution of quantity and value shall be uniform and unvarying.

In the drawings, which form a part of this application; Figure 1 is a side elevation of the machine; Fig. 2 is an end elevation; Fig. 3 is a central vertical section; and, Fig. 4 is a broken away section taken on line 4-4 of Fig. 3.

In all of the views the same reference characters indicate similar parts.

Supported upon a housing comprising vertical side members 5 and 6, a base member 7, and an upper cross member 8, is secured a materials reservoir 9. The reservoir is provided with a discharge opening 10 which communicates with a similar opening 11 made in the cross piece 8 of the housing. To the bottom of the part 8 and coaxially arranged with the opening 11 is a conduit or pipe 12 which extends to a point just a little above the base plate 7. The opening 11 is flanked by a receptacle or cylinder 13 which is located at substantially right angles to the said opening. As a matter of fact the opening 11 is completed through the cylinder. Immediately above the cylinder 13, the valve 14, which is shown in Fig. 3 as being open, permits free passage of material from the reservoir 9 to the cylinder 13. A similar valve, 15, is immediately below the cylinder 13 and the opening 11 and is shown closed, thereby cutting off communication between the cylinder 13 and the pipe or conduit 12.

For purposes of better mechanical structure I prefer to taper the valves, as shown in Fig. 4, and to secure them in their respective seats by nuts 16 and 17. The valves are 60 geared together by gear wheels 18 and 19, so that when motion is communicated to the one valve motion in the opposite direction is communicated by the train of gears to the other valve. The valves are adapted to be 65 oscillated by means of the connecting rod 20.

On the shaft 21 is secured a pulley 22 which communicates by a belt 23 with the source of power for the purpose of driving the machine. A gear pinion 24 is also secured to the shaft 21 and has geared relation with the gear wheel 25 that is secured to the shaft 26. A cam 27 is secured to the shaft 26 and is adapted to be rotated thereby.

An arm 28 is pivoted to the housing, as at 75 29, and is provided with a spring 30 which yieldingly tends to hold the arm 28 in its outward position, as shown in Fig. 3. The arm 28 is connected to a piston 29, as by slot-and-pin connection 30, and on its lower end 80 is carried roller 31, which is retained in the cam race 32. It will be observed that the cam race, 32, is opened between the points 33 and 34 for a purpose to be hereafter described.

85 A guide rod 36, for the arm 28, has reciprocating bearing in brackets 37 and 38. The object of this rod is to hold the roller 31 in the cam race 32 and to guide the arm in a constant plane in the excursion of its movement.

When the shaft 26 has been rotated one half revolution the piston, or plunger, 29 will be moved inwardly of the cylinder 13 and will substantially fill the cylinder. To 95 the shaft 26 is secured another cam 39 having a closed race-way 40, shown in dotted lines in Fig. 1. The arm 20 is provided with a roller 41 which is confined within the closed race-way 40 of the cam 39. By this 100 means the valves are oscillated.

A piston 42 is connected within the cylinder of the reservoir 9 and is urged downwardly, as by a weight 43, which is connected thereto by means of the rod 44. By 105 this means a constant and sufficient pressure is exerted upon the contents of the reservoir to cause the material therein to flow readily therefrom when the aperture 10 is opened. Of course a spring, pneumatic pressure, or 110 other means may be employed for this purpose, but I prefer the use of a weight and a

piston 42 whereby the walls of the receptacle are cleared of the material so as to clean the reservoir as the contents thereof is being discharged.

As heretofore stated, the particular exemplification illustrated is designed for depositing small quantities of gold paint upon palettes of vitreous material, such as glass plates, and to this end, I have constructed a movable platform 45, hinged at one side to the base 7 as at 46, for holding the palettes 47 during the time that the material is being deposited thereon. The plate, or palette, 47 may be fed to the platform 45, from the stack 48, and after deposit has been made upon the plate the platform 45 may be lowered, so that the plate may slide out of position on the platform and then, after restoration of the platform, another plate may be allowed to slide from the stack 48 down the incline on to the restored platform.

At each revolution of the wheel 25 the valves 14 and 15 will be alternately closed and opened by operation of the cam 39, and the piston will make one complete excursion by operation of the cam 37.

When the valve 14 is opened, as shown in Fig. 3, the plastic material contained in the reservoir 9 will be forced into the cylinder 13 at the time when the piston 29 is returning to its retracted position, the operation of the piston tending to create a vacuum in the cylinder 13 and, therefore, the material is thereby more readily forced into the cylinder and for that reason completely fills it. While this operation is taking place the valve 15 is closed. Before the piston 29 starts on its in-stroke the valve 14 is closed, and the valve 15 is opened, and the amount of material contained within the cylinder 13 is discharged through the pipe 12 upon the glass palette 47. Of course, it is understood that the passageways are always filled with material, but the quantity discharged at the end of the pipe 12 will be in exact accordance with the amount expressed from the cylinder 13. The quantity of material discharged at the end of the pipe 12, at each excursion of the piston 29, will depend entirely upon the distance that the piston 29 is permitted to move outwardly in its back-stroke, and to this end a micrometer screw 50 is employed to abut against the outer end of the piston and limit the spring retracted movement of the piston 29 when the roller 31 is opposite the cut away portion of its cam raceway and therefore movable outwardly free from cam control. When the piston 29 is permitted to move to its greatest extent in a rearward direction the roller 31 of the arm 28 may leave the race-way 32, but the termini of the race-way are inclined or tapered, as at 33 and 34, so as to engage the roller 31 and cause it to return to the race-way during the major portion of the

stroke, and by this means considerable latitude of variation may be made to vary the quantity of material discharged, or sufficient variation may be accomplished to meet all practical requirements.

While I have herein described a particular embodiment of my invention, it will be understood that variations may be made in the details of construction and arrangement thereof without departure from the spirit of the invention and within the scope of the appended claims.

What I claim is:

1. An apportioning machine comprising, in combination, a reservoir having a discharge opening, a reciprocatable piston, a cylinder co-operating therewith, flanking said opening, two valves, one on each side of said cylinder, for alternately opening and closing said opening, means for operating said valves, a constantly rotatable means for reciprocating said piston, and means for adjusting the stroke of the piston without interfering with said rotating means.

2. An apportioning machine comprising, in combination, a cylinder, a reservoir having a discharge opening therethrough, a reciprocatable piston in said cylinder, valves controlling said discharge opening on opposite sides of the cylinder, operating means for reciprocating the piston connections therewith for mechanically and alternately operating the valves in timed relation with the movement of said piston, including a power-applying part mechanically connected with the piston, and means for adjusting the length of throw of the piston.

3. An apportioning machine comprising, in combination, a cylinder, a reservoir having a discharge opening therethrough, a reciprocatable piston in said cylinder, valves controlling said discharge opening on opposite sides of the cylinder, operating means for reciprocating the piston and connections therewith for mechanically and alternately operating the valves in timed relation, including a power-applying part mechanically connected with the piston, and means for varying the limit of outward movement of the piston without affecting its limit of inward movement.

4. An apportioning machine comprising, in combination, a cylinder, a reservoir having a discharge opening therethrough, a reciprocatable piston in said cylinder, mechanically operable valves controlling said discharge opening on opposite sides of the cylinder, a rotating power part, mechanical connections between said power part and said piston for imparting reciprocating movements to the piston to bring it to an invariable position at the end of its in-stroke, and adjustable means for varying the limit of movement of the piston on its out-stroke; and mechanical means for oper-

ating the valves in timed relation to the movements of the piston.

5. An apportioning machine comprising, in combination, a cylinder, a reservoir having a discharge opening therethrough, a reciprocatable piston in said cylinder, mechanically operable valves controlling said discharge opening on opposite sides of the cylinder, rotatable means for positively moving said piston to in-stroke position, an adjustable stop for determining the outstroke position of the piston, and spring means to move the piston into contact with said stop on its outstroke.
- 10 6. An apportioning machine comprising,

in combination, a cylinder, a reservoir having a discharge opening therethrough, a reciprocatable piston in said cylinder, mechanically operable valves controlling the discharge opening on opposite sides of the cylinder, and means for mechanically reciprocating said piston and varying its range of outward movement from a predetermined unchanged limit of inward movement.

In testimony whereof I hereunto set my hand in the presence of two witnesses.

JOHN W. HASBURG.

In the presence of—

EDGAR W. BURCHARD,
MARY F. ALLEN.
